WINDOW CLEANER'S ANCHORAGE

George F. Minnis, Jr., Chicago, Ill.

Application November 12, 1934, Serial No. 752,728

3 Claims. (Cl. 20—72)

My invention relates to safety devices for window cleaners, and has among its objects and advantages the provision of improved anchorage.

In the accompanying drawing:

Fig. 1 is a perspective view of a portion of a window frame illustrating my invention applied thereto;

Fig. 2 is a sectional view along the line 2—2 of Fig. 1;

Fig. 3 is a sectional view along the line 3—3 of Fig. 2;

Fig. 4 is a perspective view of a conventional anchor and my improved anchoring bolt;

Fig. 5 is a perspective view of a different form 15 of conventional anchor showing another form of my anchoring bolt; and

Fig. 6 is a sectional view along the line 6—6 of Fig. 5.

In the embodiment selected to illustrate my 20 invention, I make use of a building wall 19 with which a conventional window frame 12 is associated. Upon each side of the window I mount a conventional window cleaner's anchor 14 comprising a plate 16 and a pair of spaced integral 25 heads 18. The plate 16 is provided with prongs 20 arranged to bury into the wood of the frame 12 when drawn thereagainst by means of the bolt 22.

Referring to Fig. 2, the bolt 22 is imbedded in 30 the frame 12 and firmly secured therein by means of a nut 24. Heretofore the anchors 14 have been secured to the frame 12 by carriage bolts. My invention comprises the provision of a safety head on the bolt 22 co-operating with the heads 18 for connection with a conventional safety belt terminal 26. My bolt is provided with a reach 28 rectangular in cross section and corresponding to the rectangular reach of an ordinary carriage bolt, which reach lies within the rectangular 40 opening 30 in the plate 16 and co-operating therewith to prevent rotation of the bolt when the nut 24 is tightened. In addition to the rectangular reach 28, I provide a rectangular reach 32 somewhat larger than the reach 28, whereby 45 a shoulder is provided for bearing against the plate 16, as indicated at 34 in Fig. 2, when the nut 24 is tightened. I provide a head 36 in addition to the rectangular part 32, which head is of a size and shape corresponding to the heads 18 50 and arranged in alignment therewith.

In Figs. 2 and 6, the safety belt terminal 26 comprises in part two spaced flanges 38 arranged to pass underneath the heads 18 and 36 by an endwise movement of the terminal. Such terminals are usually provided with a spring 40 hav-

ing an end 42 bent to abut one of the heads 18 for latching the terminal to the anchor. The arrangement of the head 36 is such that accommodation is provided for the end 42 in the same way as in the absence of the head.

In the past, many accidents have occurred because of defective anchors. Many plates 16 have been broken transversely in alignment with the opening 30. Such a break leaves no anchorage for the belt terminal 26 associated therewith. 10 The conventional carriage bolt connection provides no anchorage for the terminal 26 other than as a means for clamping the plate 16 to the frame 12. In connection with belt terminals of the type illustrated an enormous leverage is applied to the lower head 18 when a heavy weight 15 pulls on the window cleaner's belt 44 connected with the terminal through the medium of the eyelet 46. This leverage is transmitted to the plate 16 and is concentrated along the transverse line above mentioned in alignment with the opening 30. When one anchor breaks a window cleaner is apt to fall, which falling frequently results in fatal injury to the window cleaner.

Because of my construction, complete safety 20 is attained because of the fact that the terminal 26 is connected directly with the bolt 22 through the medium of its head 36. Regardless of what 25 happens to the anchor 14, the terminal 26 will remain connected with the head 36. The anchor bolt 22 is safe because of its firm anchorage in 30 the window frame 12 and because of its enormous tensile strength.

My invention is applicable to conventional anchors and belt terminals and may be associated 35 with the anchor before or after installation. The bolt may easily be substituted for the conventional carriage bolt in buildings already equipped and the single bolt simplifies the work of installation, in addition to eliminating the necessity for 40 boring special holes and making other special connections.

In Figs. 5 and 6, I illustrate a slightly different 45 form of construction designed for use in connection with anchors 48 having heads 50 offset with respect to the vertical central axis of the plate part 52. In some installations it is necessary to use anchors of this type to provide the necessary accommodation for the terminal 26 because of structural obstructions. The bolt 54 embodies 50 a conventional rectangular reach 56 lying within the rectangular opening in the plate 52 and has a large head 58 arranged to bear against the plate 52 by pressing the plate against its associated window frame. I provide the head 58 55

with an integral neck 60 terminating in an integral head 62. The neck 60 and the head 62 are offset with respect to the axis of the bolt 54 to align the head 62 with the heads 50 in the 5 same way as the head 36 aligns with the heads 18.

Without further elaboration, the foregoing will 10 so fully explain my invention that others may, by applying current knowledge, readily adapt the same for use under various conditions of service.

I claim:

1. In combination with a window cleaner's anchor comprising a plate having spaced heads for connection with a belt terminal, said plate 15 having an opening arranged in a line drawn centrally through the heads, and an anchor bolt passing through said opening, said anchor bolt being provided with a head corresponding to said 20 heads and having a second head arranged to bear against said plate for clamping the same to a supporting structure, the two heads associated with the bolt being connected together by a neck, and said spaced heads and one of the heads asso-

ciated with the bolt being arranged in alignment for connection with a belt terminal.

2. Window cleaner's equipment comprising a plate having two spaced heads for connection with a belt terminal, said plate being provided 5 with an opening between the spaced heads and the latter being positioned to one side of the plate, an anchoring bolt passing through said opening and having a head bearing against said plate, and a safety head carried by the head on 10 the bolt and positioned to one side of the head for alignment and co-operation with said spaced heads.

3. Window cleaner's equipment comprising a plate having two spaced heads, an anchoring bolt 15 passing through said plate and having a head positioned between said two heads, a belt terminal including spaced flanges arranged to be positioned underneath the three heads, and a latch member carried by said belt terminal and having 20 an end shaped to be positioned between the third head and one of said two heads for latching relation with the latter.

GEORGE F. MINNIS, JR.
